UNITED STATES PATENT OFFICE

158,575

COMBINATION COMB HOLDER AND PIN TRAY

Emery M. Hanrahan, Kenosha, Wis.

Application September 12, 1949, Serial No. 4,961

Term of patent 14 years

(Cl. D86—10)

To all whom it may concern:

Be it known that I, Emery M. Hanrahan, a citizen of the United States and resident of Kenosha, in the county of Kenosha and State of Wisconsin, have invented a new, original, and ornamental Design for a Combination Comb Holder and Pin Tray, of which the following is a specification, reference being had to the accompanying drawing, forming part thereof.

I claim:

The ornamental design for a combination comb holder and pin tray, as shown.

EMERY M. HANRAHAN.
